UNITED STATES PATENT OFFICE.

HOWARD E. MARSH, OF LOS ANGELES, CALIFORNIA, ASSIGNOR OF ONE-HALF TO WILLIAM P. WAGY, OF LOS ANGELES, CALIFORNIA.

BRIQUET-MACHINE.

No. 813,657.

Specification of Letters Patent.

Patented Feb. 27, 1906.

Application filed March 13, 1905. Serial No. 249,761.

To all whom it may concern:

Be it known that I, HOWARD E. MARSH, a citizen of the United States, residing at Los Angeles, in the county of Los Angeles and State of California, have invented a new and useful Briquet-Machine, of which the following is a specification.

This invention relates to that class of briquet-machines in which a series of mold-blocks move through an orbit and over a molding-drum, the formation of the briquet being effected while a mold-block is in conjunction with the molding-drum and the ejection of the briquet from the mold-block occurring when the mold-block has reached another point in its orbit, the filling of the mold-block taking place at still another point in its orbit; and one of the important objects of the invention is to lessen the amount of power required to move the mold-blocks through their orbit.

Another important object is to provide a novel mold-block and compressing-plunger which will produce a more perfectly finished briquet than heretofore.

Another object is to provide novel and efficient mechanism for intermittently moving the mold-blocks step by step through their orbit and maintaining a mold-block stationary while the compression of the briquet is being accomplished.

Another important object is to provide a throw-out mechanism by which the compressing mechanism may be thrown out of operation without stopping the machine or stopping any of the other functions of the machine.

Another object is to provide means for positively holding a molding-drum stationary and in perfect register with a mold-block during the compression of the briquet against the molding-drum.

Another object is to provide a novel and efficient mechanism for feeding the briquet material into the mold-blocks, whereby a definite amount of material is delivered to each matrix or molding-cavity therein.

Another object is to provide a novel mechanism for actuating the molding-plungers in ejecting the briquet.

Other objects and advantages of the invention will appear in the following description.

This invention is an improvement on the

briquet-machine for which I filed application June 2, 1904, Serial No. 210,768, (patented April 4, 1905, No. 786,773;) and an object of the invention is to do away with the stress and strain which was found in actual practice to exist with the former machine. This object is in part accomplished by guiding the mold-boxes by means which are inclined downwardly in the direction toward which the mold-boxes travel, so that the weight of the mold-boxes is applied to assist in driving the machine except while engaging the molding-drum.

The accompanying drawings illustrate the invention.

Referring to the drawings, Figure 1 is a plan view of the invention. Fig. 2 is a section on the line $x^2 x^2$, Fig. 1. Fig. 3 is a side elevation of the invention. Fig. 4 is a sectional view on line $x^4 x^4$, Fig. 2. Fig. 5 is a sectional view on line $x^5 x^5$, Fig. 2. Fig. 6 is a side elevation of part of the intermittent gearing for actuating the molding-drum. Fig. 7 is a side elevation, partly in section, of part of the throw-out mechanism. Fig. 8 is a sectional view on line $x^8 x^8$, Fig. 1. Fig. 9 is a perspective view, the foreground of which is a section taken diametrically through the molding-cavity or matrix of a molding-block. The molding-plunger is shown in perspective in place. Fig. 10 is a perspective of part of the throw-out mechanism, showing the spring-buffer. Fig. 11 is a perspective of a slide for positioning the molding-drum. Fig. 12 is a side view of the stop-motion cam.

1 designates the base of the machine, having side frames 2. The head-casting 3 of the frame is fastened to the side frames 2 by bolts 4, while the foot-casting 5 of the machine is fastened to the side frames 2 by similar bolts 4, as shown in Fig. 3. A drum-shaft 6 is mounted in bearings 7, which are provided on each side of the frame. The axis of the shaft 6 is on a line with the joint between the head-casting 3 and the side frames 2, the lower sections of the journals 7 being cast on the side frames 2 and the upper sections of the journals 7 being cast on the head 3.

Mounted upon the shaft 6 is a molding-drum 8, having in this embodiment twelve flat faces 9, each face forming a working or molding bed against which the briquets are formed during the intervals between consecutive steps of the drum in its intermittent rotation.

The upper end of the head 3 is provided with journals 10, in which is mounted a main shaft 11, upon which is a fly-wheel 12, the outer end of the shaft 11 being further supported by a journal 13. Mounted rigidly on the shaft 11 is a compressing-cam 14, which works against an intermediate throw-out mechanism comprising a pendent spring-buffer 15, formed of two arms pivoted to a shaft 16 and carrying at their lower ends a roller 17, against which the cam 14 works. (See Figs. 1, 2, and 10.) The shaft 16 is mounted in a yoke 18, which is carried by a shaft 19, mounted in brackets 20 on the side frames 2, the yoke 18 having an upright hand-lever 21, by means of which the yoke may be rocked up or down. The ends of the shaft 16 lie within slotted brackets 22, the slots of which are curved concentrically with the shaft 19 and which serve not only to guide the shaft 16 when the yoke 18 is rocked, but also to form a rigid bearing for the shaft, especially when the shaft is in the lower part of the slots in working position.

Pivoted to the shaft 16, between the arms of the yoke 18, is a pendent plunger-buffer 23, (see Figs. 2, 7, and 10,) having a head 24, which carries in this embodiment three anti-friction thrust-blocks, each thrust-block comprising a disk 25, which is rotatably connected with the head 24 by a screw 26, the head of which lies within a recess 27, formed in the head 24, there being a series of balls 28 arranged between the head 24 and the thrust-block 25, which relieve the friction of the thrust-block 25 against the head 24 when the former is rotated during compression of a briquet.

The lower eyes of the spring-buffer 15 have studs 29. Compression-springs 30 are interposed between the spring-buffer 15 and the plunger-buffer 23, being supported by the studs 29, as shown in Figs 2 and 10. Projecting down from the yoke 18 is an arm 31, having a stud 32, and the plunger-buffer 23 has a similar stud 33 in line with the stud 32, there being a compression-spring 34 interposed between the plunger-buffer 23 and the arm 31 and retained in position by the studs 32 and 33. When this throw-out mechanism stands in the position shown in Fig. 2, with the shaft 16 in the bottom of the slotted brackets 22, the spring-buffer roller 17 is in the pressure-line between cam 14 and the molding-drum, being in working position in front of the cam 14, while by throwing the lever 21 to the left the shaft 16 is moved to the top of the slotted brackets 22, which raises the spring-buffer roller 17 and plunger-buffer 30 bodily therewith out of the pressure-line and out of working position with the cam 14, the spring 34 maintaining the spring-buffer and plunger in normal position relatively to the yoke 18.

Rigidly mounted on the shaft 11 on the

outside of each of the side frames 2 are bevel-gears 35, each of which meshes with a bevel-gear 36, carried on a side shaft 37, mounted on each side of the side frames 2 in journals 38. The lower end of each shaft 37 carries a pair of cams 39, (see Figs. 6 and 12,) which extend through three hundred and sixty degrees and form a helical slot 40, which extends through one hundred and eighty degrees and which at each end merges into terminal grooves 41, each of which extends through ninety degrees and lies in the plane of rotation of the shaft 37.

Mounted on the shaft 6 on each side of the side frames 2 are disks 42 with pins 42^a, which are consecutively engaged by the respective stop-motion cams just described, there being one pin 42 for each flat face 9 of the molding-drum. The shafts 37 are each given one rotation for each rotation of the shaft 11, and as they rotate the pins 42^a of the disks 42 are advanced step by step by the cams 39. While the pins lie within either of the terminal slots 41 the disks and drum are stationary, although the shafts 37 continue revolving, the movement of the drum being performed by the passage of the pins through the intermediate helical portion of the slot 40. Thus the molding-drum is rotated step by step, bringing a new face 9 into position for each complete revolution of the shaft 11, the movement being accomplished during half of a revolution of the shaft 11 and the face being held stationary during the other half of the revolution of the shaft 11. On each end of the molding-drum 8 are bosses 43, the function of which will be described later.

Each side frame 2 is provided with an ovoidal orbital guide formed as a groove 44, and arranged to travel around the grooves is a series of mold-blocks 45, each end of each mold-block having a pair of studs 46, which ride within the grooves 44. The upper run of each groove 44 is inclined with its lower end at the foot of the machine, while the lower run of each groove is also inclined with its lower end at the head of the machine. Thus the mold-blocks while in the upper run of the grooves may be moved wholly or partially by gravity from the head of the machine toward the foot and over the small end of the orbit, and in returning from the foot to the head of the machine on the lower run of the grooves they will also travel wholly or partially by gravity. Thus in order to maintain a movement of the entire series of mold-blocks through their orbit practically all the power that is required will be to lift the mold-blocks around the semicircular curve at the head end of the machine, as they will move through the other part of their orbit either wholly or partially by gravity, according to the dimensions and proportions employed. In any event the movement of the mold-blocks through the orbit will be accomplished

back into retracted position, as shown in Fig. 2. Upon the retraction of the filling-plungers 63 from the mold-block the series of mold-blocks are shifted to bring another mold-block into place before the filling-plungers 63; but this movement of the mold-blocks does not occur until the plungers have moved back sufficiently to clear the mold-block which they were filling, the gearing of the stop-motion cams being arranged to produce this action. As a mold-block reaches the molding-drum its pins 46 are engaged by the bosses 43 and it is lifted step by step until it comes into a position in front of the compressing mechanism, and when in such position the heads 50 of the plungers 48 stand directly in front of and in register with the heads 25 of the plunger-buffer 23, and as the latter is moved forward through the medium of the cam 14 and intermediate mechanism before described the plungers 48 are simultaneously pushed in and compress the material in the three molding-cavities into briquets, the compression being accomplished by the resistance afforded by the compression-springs 29, the tension of which is such that they will impart sufficient compression to the briquets before yielding or collapsing. As the plungers 48 are moved toward the flat face 9 in forming the briquets each plunger is given an axial movement by its curved grooves 51 riding over the pins 53, so that the plunger 48 packs the briquet material more evenly than if the compression of the briquet were accomplished without the rotative movement. This rotative movement of the plunger also gives a better finish to the briquet. As the plungers 48 in moving in are thus given a slight rotative movement their heads 50 are also turned, and as the pressure against the heads 50 is borne by the thrust-bearings 25 the rotative friction is relieved by the balls 28. As the mold-block is moved step by step along in its orbit it finally comes under the ejecting-plate 80, and when directly under the plate 80 and while stationary the ejecting-plate 80 is moved down through the medium of the before-described mechanism and bearing upon the heads of the three plungers in the mold-block expels the briquets from the mold-block, and they fall upon the conveyer-belt 83. During the expulsion of the briquets from the mold-blocks the plungers 48 are not turned axially, as the straight slots 42 then ride over the pins 53. After the expulsion of the briquet from the mold-block the ejecting-plate 80 raises and the mold-block moves step by step into position again in front of the filling-plungers 63, thus completing one cycle of its functions. The compression of the briquets may be stopped at any time by throwing the handle 21 to the left, which will pull the spring-buffer 17 and plunger-buffer 30 up out of engagement with the cam 14,

and the machine will continue to run and carry on its other functions without compressing. While the throw-out mechanism is thus positioned, the spring 34 holds the plunger-buffer 23 in a constant position relatively to the shaft 19, so that by moving the handle 21 in the other direction to restore the compressing function the plunger-buffer 23 is guided into place without interfering with the heads of the plungers. 75

It is to be noted that the guide 44 is downwardly inclined or directed throughout all that portion of the orbit of said blocks except a certain portion less than half the circumference of the molding-drum, where the entire work of lifting the blocks is accomplished by such drum, which is the initial element for applying power to said blocks. By this construction the force of gravity assists in moving the blocks at all points of the orbit 85 except where the blocks are in direct connection with the initial power-applying element by which said blocks are directly lifted and again started on the downward course of their orbit. 90

What I claim is—

1. In a briquet-machine comprising a series of disconnected mold-blocks, means for supporting the mold-blocks and guiding them in an orbit, the upper and lower runs of the 95 orbit being inclined downwardly in the direction in which the blocks travel, and means for directly lifting the mold-blocks from the lower run to the upper run.

2. In a briquet-machine, a series of mold-blocks, means for feeding material to the mold-blocks, and means for compressing the material within the mold-blocks embracing a throw-out mechanism bodily movable into or out of the pressure-line. 100

3. In a briquet-machine, a series of disconnected mold-blocks, means for supporting the mold-blocks and guiding them downwardly through a portion of their orbit, and means for lifting the mold-blocks from the 110 lower end to the upper end of such portion.

4. In a briquet-machine, a molding-drum, a series of mold-blocks, means for supporting and guiding said mold-blocks in an orbit over said molding-drum, means including a stop-motion cam for intermittently rotating the molding-drum and advancing the mold-blocks through the orbit. 115

5. In a briquet-machine, a series of mold-blocks each having a molding-cavity, a plunger in said cavity for compressing the briquet, means for coacting with the plungers consecutively and operating them and means for axially turning each plunger during its compression of the briquet. 120

6. In a briquet-machine, a mold-block having a molding-cavity, a plunger therein, means for imparting a combined longitudinal and axial movement to the plunger for compressing the briquet, and means for impart- 130

much easier than in structures where the mold-blocks are moved through an elliptical orbit—that is to say, with the top and bottom runs of the orbit substantially horizontal—
 5 as in such structures, whether the mold-blocks are pulled around by a chain or pushed bodily in an unconnected series, the friction to be overcome, owing to the weight of the mold-blocks upon their guide, is considerable; but
 10 in the present construction the mold-blocks travel downwardly by gravity, being hoisted from the bottom run to the top run positively. In the present embodiment this hoisting of the mold-blocks is accomplished
 15 by the bosses 43, which engage between each pair of pins 46 on each end of each mold-block as they come into conjunction therewith and acting upon the forward pins of the mold-block elevate the same through the
 20 semicircular portion of the orbit.

Each mold-block 45 is provided with one or more molding-cavities or matrices 47, in each of which lies a molding-plunger 48, having a stem 49, which projects through the
 25 back wall of the mold-block and which preferably has a head 50. Each stem 49 is provided with a pair of diametrically opposite curved grooves 51, the lower ends of the curved grooves merging with straight grooves 52, parallel to the axis of the plunger, while
 30 projecting from the mold-block 45 into the grooves in the stem are pins 53. Thus as the plunger is moving in the upper part of the molding-cavity 47 it will be given a combined
 35 rectilineal and axial movement, while when working in the lower part of the cavity 47 it will take a purely rectilineal movement. The molding-cavities of the mold-blocks are supplied with briquet material at the foot of the
 40 machine, and the compression of the briquet is accomplished at the head end of the machine, the compression being accomplished by the cam 14 pressing against the spring-buffer 17, which, through the medium of the
 45 spring 29 and plunger-buffer 23, pushes down the plunger 48 toward the flat face 9 of the molding-drum, the spring 29 being made stiff enough to secure the necessary compression of the briquet before yielding appreciably.
 50 The compression of the briquet is performed while the molding-drum is stationary, and in order to hold the molding-drum positively stationary during compression a device is employed which comprises a pair of
 55 slides 54, one of which is arranged on each side of the head-casting 3, each slide having a head 55, which is adapted to press against the adjacent flat face 9 of the molding-drum to position the same. Each slide 54 has an
 60 arm 56, carrying a roller 57, and the slides 54 are both simultaneously moved toward and against the flat face 9 of the molding-drum by means of cams 58, which work against the respective rollers 57, the cams 58 being preferably formed integral with the cam 14. In

order to normally hold the slides 54 retracted, so that their heads 55 freely clear the molding-drum to allow the same to rotate, compression-springs 59 are provided, one for each head 55, each spring 59 being supported by a pin 60, projecting from the head-casting 3, the head-casting being recessed on each side to accommodate the slides 54 and springs 59.

The feeding mechanism in this embodiment comprises a hopper 61, in the bottom of which are formed three tubular extensions 62, in each of which is mounted a plunger 63, the plungers 63 being connected by a pintle 64 with a yoke 65, which has an arm 66 with a sleeve 67, through which a cross-bar 68 passes. The bar 68 is suspended by arms 69 and 70, which are hung from a shaft 71, which is supported in journals 72, formed on brackets 73 on the side frames 2.

Mounted on the shaft 11 are eccentrics 74, 85 each of which operates an eccentric-rod 75, each eccentric-rod 75 being connected with one of the arms 70, as shown in Fig. 2. Each eccentric-rod 75 is preferably provided with a turnbuckle 76 for adjusting its length, and each arm 70 has a series of bolt-holes 77 for the attachment of the eccentric-rods, providing means for adjusting the stroke of the plungers 63. In order to clean the faces of the mold-blocks of any material which may have collected therein, a rotating brush *b* is employed, which carries a pulley *p*, driven by a belt. (Not shown.)

Rigidly fastened to the shaft 71 is a sleeve 78, having an arm 79, which carries an ejecting-plate 80, the length of which is sufficient to embrace the three plungers in each mold-block, as shown in Fig. 1.

A bracket 81 is attached to the side frames 2 and supports a pulley 82, over which a conveyor-belt 83 runs, upon which belt the briquets fall when expelled from the mold-blocks.

In operation as the shaft 11 revolves the molding-drum is rotated step by step, as above described, through the medium of the stop-motion cams, the mold-blocks adjacent the drum being carried around the molding-drum by the bosses 43 and moving through the rest of their orbit mainly or wholly by gravity, according to the degree of incline of the upper and lower runs of the orbit. The filling-plungers 63 are reciprocated through the medium of the arms 70, which are operated by the eccentrics 74. The hopper 61 is filled with material to be formed into briquets, and as the filling-plungers 63 are retracted the material from the hopper 61 falls down into the tubular extensions in front of the retracted plungers, so that as the filling-plungers move forward they push material before them into the three molding-cavities in the mold-block which lies in front of the plungers. As the briquet material is thus pushed into the molding-cavities compressing-plungers 48 in the cavities are pushed

ing a rectilineal movement only to the plunger while expelling the briquet from the mold-block.

7. In a briquet-machine, a series of mold-blocks, means for supporting and guiding the same in an orbit, a molding-drum coacting with the mold-blocks, and means for intermittently bearing directly against the molding-drum to hold the molding-drum rigid during the compression of each briquet.

8. In a briquet-machine, means provided with a face against which a briquet is pressed, a mold-block movable into conjunction with said face, and within which the briquet is formed, a plunger in the mold-block, and resilient means for operating the plunger, and means for moving the resilient means bodily out of the pressure-line.

9. In a briquet-machine, means for compressing a briquet comprising a collapsible device, the working tension of which does not exceed the pressure to be imparted to the briquet, and means for moving the collapsible device bodily out of the pressure-line.

25 10. In a briquet-machine, means for compressing a briquet comprising a compressible element, the resistance of said compressible element being not greater than the resistance afforded thereto by the briquet when compressed to a definite degree, and means for moving the compressible element bodily out of the pressure-line.

11. In a briquet-machine, a series of disconnected mold-blocks, means for guiding the mold-blocks downwardly through a portion of their orbit, and a molding-drum arranged to lift the blocks from the lower end to the upper end of said portion.

12. In a briquet-machine, a series of mold-blocks, means for advancing the mold-blocks step by step through an orbit, a hopper having a tubular extension, a plunger in said extension for pushing material from the hopper into a mold-block, an intermediate shaft, pendent arms on said shaft, a connection from the plunger to the pendent arms, a main shaft, an eccentric thereon, and a rod connecting the eccentric with a pendent arm.

13. In a briquet-machine, a series of mold-blocks, means for advancing the mold-blocks step by step through an orbit, a hopper having a tubular extension, a plunger in said extension for pushing material from the hopper into a mold-block, an intermediate shaft, pendent arms on said shaft, a connection from the plunger to the pendent arms, a main shaft, an eccentric thereon, a rod connecting the eccentric with a pendent arm, and means for attaching the eccentric-rod at various points on the pendent arm to adjust the stroke of said plunger.

14. In a briquet-machine, a base having side frames each of which has an ovoidal groove, the upper run of the grooves being inclined in one direction from the horizontal,

and the lower run of the grooves being oppositely inclined, a series of disconnected mold-blocks, and means on the mold-blocks projecting into the grooves for supporting the mold-blocks.

70 15. In a briquet-machine, a base with side frames, each side frame having an ovoidal groove, the upper run of the grooves being inclined in one direction from the horizontal, and the lower run of the grooves being oppositely inclined, a series of disconnected mold-blocks between the side frames and a pair of pins on each end of each mold-block projecting into the adjacent groove.

75 16. In a briquet-machine, a base having side frames each of which has an ovoidal groove, the upper run of the grooves being inclined in one direction from the horizontal, and the lower run of the grooves being oppositely inclined, a series of disconnected mold-blocks, means on the mold-blocks projecting into the grooves for supporting the mold-blocks, and means for elevating the mold-blocks from the lower run to the upper run of the grooves.

80 90 17. In a briquet-machine, a base with side frames, each side frame having an ovoidal groove, the upper run of the grooves being inclined in one direction from the horizontal, and the lower run of the grooves being oppositely inclined, a series of disconnected mold-blocks between the side frames, a pair of pins on each end of each mold-block projecting into the adjacent groove, and a molding-drum having lugs for engaging said pins to lift the mold-blocks from the lower run to the upper run of said grooves.

95 18. In a briquet-machine, a series of mold-blocks, means for supporting and guiding the mold-blocks through an orbit, plungers in the mold-blocks having stems, a main shaft, a cam carried thereby, and a throw-out mechanism between said cam and the path of the mold-blocks.

100 110 19. In a briquet-machine, a series of mold-blocks, means for supporting and guiding the mold-blocks through an orbit, plungers in the mold-blocks having stems, a main shaft, a cam carried thereby, a throw-out mechanism between said cam and the path of the mold-blocks, the throw-out mechanism comprising a pivoted spring-buffer, a pivoted plunger-buffer, and a spring between the two buffers.

115 120 20. In a briquet-machine, a series of mold-blocks, means for supporting and guiding the mold-blocks through an orbit, plungers in the mold-blocks having stems, a main shaft, a cam carried thereby, a throw-out mechanism between said cam and the path of the mold-blocks, the throw-out mechanism comprising a pivoted spring-buffer, a pivoted plunger-buffer, a spring between the two buffers, and a thrust-bearing carried by the plunger-buffer for working against the stem of the plunger.

125 130 21. In a briquet-machine, a series of mold-

blocks movable through an orbit, a shaft, a cam on the shaft, a throw-out mechanism between the cam and path of the mold-blocks comprising a pivoted spring-buffer, a plunger-buffer pivoted concentric with the spring-buffer, a spring between the two buffers, and means for lifting said buffers.

22. A series of mold-blocks movable through an orbit, a shaft, a cam on the shaft, a throw-out mechanism between the cam and the path of the mold-blocks comprising a rock-shaft, a yoke carried by said rock-shaft, a hand-lever for operating said rock-shaft, a spring-buffer pivoted to said yoke and working against said cam, a plunger-buffer pivoted to said yoke, and a spring between the two buffers.

23. A series of mold-blocks movable through an orbit, a shaft, a cam on the shaft, a throw-out mechanism between the cam and the path of the mold-blocks comprising a rock-shaft, a yoke carried by said rock-shaft, a hand-lever for operating said rock-shaft, a spring-buffer pivoted to said yoke and working against said cam, a plunger-buffer pivoted to said yoke, a spring between the two buffers, and means for yieldingly holding said buffers in substantially constant relation to said yoke irrespective of the position of the yoke.

24. A series of mold-blocks movable through an orbit, a shaft, a cam on the shaft, a throw-out mechanism between the cam and the path of the mold-blocks comprising a rock-shaft, a yoke carried by said rock-shaft, a hand-lever for operating said rock-shaft, a spring-buffer pivoted to said yoke and working against said cam, a plunger-buffer pivoted to said yoke, a spring between the two buffers, an arm depending from said yoke and having a stud, a stud on the plunger-buffer, and a spring supported by said studs between said arm and the plunger-buffer.

25. In a briquet-machine, a base with side frames, a series of mold-blocks movable in an orbit, means on the said frames for supporting the mold-blocks, a molding-drum having working faces over which the mold-blocks pass, a slide mounted in each side frame adjacent the molding-drum, a head on each slide for pressing against the working face of the molding-drum, and means for pressing said slides toward the drum to force the heads against the working faces of the molding-drum.

26. In a briquet-machine, a base with side frames, a series of mold-blocks supported by the side frames, a molding-drum having working faces with which the mold-blocks coact, means for intermittently rotating the molding-drum and moving the mold-blocks, a slide on each side frame adjacent the molding-drum, a head on each slide, and means for forcing the slides toward the molding-

drum while the latter is stationary between successive steps to force the heads against the adjacent working face of the molding-drum.

27. In a briquet-machine, a base with side frames, a series of mold-blocks supported by the side frames, a molding-drum having working faces with which the mold-blocks coact, means for intermittently rotating the molding-drum and moving the mold-blocks, a slide on each side frame adjacent the molding-drum, a head on each slide, a main shaft carried by the side frames, cams on the shaft, a roller carried by each slide and working against its respective cam.

28. In a briquet-machine, a series of mold-blocks movable through an orbit, plungers in the mold-blocks, a rotating cam, a throw-out mechanism between the cam and a plunger for operating the same comprising a rock-shaft, a yoke on the rock-shaft, a hand-lever for operating the yoke, slotted guide-brackets, a shaft carried by the yoke, the ends of which are guided by the slotted brackets, a spring-buffer mounted on the shaft, a plunger-buffer mounted on the shaft, and a spring between the two buffers.

29. In a briquet-machine, a series of mold-blocks movable through an orbit, plungers in the mold-blocks, a rotating cam, a throw-out mechanism between the cam and a plunger for operating the same comprising a rock-shaft, a yoke on the rock-shaft, a hand-lever for operating the yoke, slotted guide-brackets, a shaft carried by the yoke, the ends of which are guided by the slotted brackets, a spring-buffer mounted on the shaft, a plunger-buffer mounted on the shaft, a spring between the two buffers, an arm carried by the yoke, a stud on the arm, a stud on the plunger-buffer, and a spring supported by said studs between said arm and the plunger-buffer.

30. In a briquet-machine, a series of mold-blocks movable through an orbit, plungers in the mold-blocks, a rotating cam, a throw-out mechanism between the cam and a plunger for operating the same comprising a rock-shaft, a yoke on the rock-shaft, a hand-lever for operating the yoke, slotted guide-brackets, a shaft carried by the yoke, the ends of which are guided by the slotted brackets, a spring-buffer mounted on the shaft, a plunger-buffer mounted on the shaft, a spring between the two buffers, an arm carried by the yoke, a stud on the arm, a stud on the plunger-buffer, a spring supported by said studs between said arm and the plunger-buffer, a head revolvably mounted on the plunger-buffer, and a series of balls between the head and buffer.

31. In a briquet-machine, a series of mold-blocks movable through an orbit, a shaft, pins on each mold-block, and means operated

by the shaft and engaging the pins for imparting an intermittent movement to the same.

32. In a briquet-machine, a series of mold-blocks movable through an orbit, and having flat faces, a molding-drum provided with flat faces for coacting with the flat faces of the mold-blocks and means intermittently movable toward the molding-drum and bearing 5 against the flat faces in consecutive order for holding the molding-drum rigidly stationary.

33. In a briquet-machine, a series of mold-blocks movable through an orbit, a shaft, pins on each mold-block, means operated by 15 the shaft and engaging the pins for imparting an intermittent movement to the same, and means for intermittently operating the molding-drum to impart a step-by-step movement to the mold-blocks.

34. In a briquet-machine, a series of mold-blocks movable through an orbit, pins on the ends of the mold-blocks, a molding-drum having bosses for engaging said pins, and means for moving said molding-drum where- 20 by the mold-blocks are moved by the pins co-acting with the bosses.

35. In a briquet-machine, a base with side

frames, each side frame having a groove; a series of mold-blocks, a pair of pins on each end of each mold-block projecting into the 30 adjacent groove in the said frame, a molding-drum over which the mold-blocks pass and means operated by the molding-drum for causing the mold-blocks to travel along said grooves.

36. A briquet-machine comprising a series of disconnected mold-blocks, means for supporting the mold-blocks and guiding them in an orbit, said means comprising studs projecting from said mold-blocks and a slotted 40 support in which said studs travel, the upper and lower runs of the orbit being inclined downwardly in the direction in which the blocks travel, and means for directly lifting the mold-blocks from the lower run to the up- 45 per run.

In testimony whereof I have hereunto set my hand, at Los Angeles, California, this 28th day of February, 1905.

HOWARD E. MARSH.

Witnesses:

GEORGE T. HACKLEY,
ARTHUR P. KNIGHT.
